ADJUSTABLE FOOT FOR LADDERS.

1,088,168.

Specification of Letters Patent. Patented Feb. 24, 1914.

Application filed March 11, 1913. Serial No. 753,513.

To all whom it may concern:

Be it known that I, WILLIAM D. OSTERHOUDT, a citizen of the United States, and a resident of Poughkeepsie, Dutchess county, 5 State of New York, have invented certain new and useful Improvements in an Adjustable Foot for Ladders, of which the following is a specification, accompanied by drawings.

This invention relates to an adjustable 10 foot for ladders and the objects of the invention are to improve upon such devices by taking the strain off the lower round of the ladder, and distributing the strain, so that it is taken by the lower ends of the ladder 15 sides and by a metal brace rod extending between said lower ends. In this manner, the device becomes more efficient, does not materially increase the length of the ladder and strengthens the ladder while at the same 20 time providing for twisting strains when the ladder is used in situations in which the strain does not fall equally upon both sides of the ladder.

Another important object of the invention 25 is to provide means for automatically locking the ladder to the adjustable foot when the weight of a person is placed on the ladder, so that the ladder cannot slip sidewise along the foot. Unless the lock is automatic in operation, there is no certainty 30 that the operator will lock the foot to the ladder manually, as by a pin and slot, or by a pin and segment, as usually provided, because this important operation may be forgotten, and an accident may result. With 35 my improved device, however, the ladder may be set at any desired position on the foot, and then the act of mounting the ladder, firmly locks the foot to the ladder. In 40 fact, with a farm ladder of ordinary weight, the weight of the ladder itself is usually sufficient to lock the parts together, since my improved locking device depends for its operation upon an angular displacement of the 45 ladder relatively to the plane of the ladder foot.

The invention is shown in one of its preferred forms in the accompanying drawings, in which—

50 Figure 1 is a side elevation of a ladder having my improved adjustable foot attached thereto; Fig. 2 is an enlarged detail transverse sectional view of the stirrup clamp on the line 2—2 of Fig. 1, looking in 55 the direction of the arrows; Fig. 3 is an in-

side face view of the lower portion of one side of the ladder showing the construction of one of the guide plates; Fig. 4 is a perspective view of the ladder leaning against a wall, showing how the stirrup clamp automatically grips the bow-shaped ladder foot, Fig. 5 is an enlarged detail sectional view of the stirrup clamp tipped into the gripping position shown in Fig. 4, and Fig. 6 is an enlarged detail sectional side elevation 60 of the lower portion of the ladder, showing the difference in angle between the plane of the foot and the plane of the ladder sides when the ladder is placed against a wall or other support.

Referring to the drawings, A represents an ordinary farm ladder by way of illustration, although the invention may be applied to any suitable ladder, and B represents an arched or bow-shaped adjustable 65 foot having the gripping toes C. The sides D of the ladder as shown are provided with the usual rounds or treads E and in order to connect the adjustable foot to the ladder and take the strain off the lower round, I provide a metal brace rod F adapted to be secured transversely between the lower ends 70 of the ladder sides. As shown, this brace rod extends through apertures in the ladder sides and is bolted in place as by means 75 of the nuts G and H.

In order to produce a more rigid and serviceable construction, guide plates J are preferably secured to the inside portions 80 of the lower ends of the ladder sides, through which guide plates the brace rod F passes. The guide plates J may be secured to the ladder sides as by means of the screws K or other suitable fastening means, and as 85 shown, these guide plates have longitudinal slots L through which brace rod F passes, because the location of the brace rod longitudinally in the guide plate necessarily varies with ladders of different width. The brace rod will be located nearer the top of 90 the slot with wider ladders and with narrower ladders the brace rod will be located nearer the bottom of the slot, since the relation between the brace rod and the arched foot remains relatively fixed and the angle 95 between the brace rod and the foot remains fixed.

The guide plates J as shown are recessed at O between the lugs P for the reception 100 of the foot and if desired, the lower ends 105

of the ladder sides may be beveled or cut away at Q to accommodate the foot. The lugs P are preferably apertured to receive the pins R shown in this instance having winged finger pieces S and nuts T.

In accordance with this invention a stirrup clamp U is pivotally hung from the brace rod F and provided with an angular opening through which the foot passes. Collars W and X on the brace rod serve to hold the stirrup clamp centrally of the rod, but permit the stirrup clamp to swing or rock about the rod. The cross section of the foot B is preferably angular as shown in Figs. 10 2 and 5 and when the arched foot is held in the plane of the sides of the ladder, or 15 when the ladder is held upright over the arched foot in the same plane as the plane of the foot, the ladder may be moved longitudinally along the foot without binding until the ladder has been adjusted in the desired position. Angular displacement, 20 however, of the plane of the ladder relatively to the plane of the foot causes the foot to bind in the stirrup clamp, as illustrated in Fig. 5, thereby preventing the ladder from slipping sidewise longitudinally along the foot. In Fig. 6 a view is 25 shown of the ladder leaning against the wall of a building with the foot upon the ground, from which it will be seen that the body portion of the foot is tipped or arched in the angular opening V of the stirrup, so that the foot and the stirrup are clamped to 30 each other. Any increased weight thrown upon the ladder, as the weight of the operator who mounts the ladder, increases the binding effect of the stirrup upon the foot. The foot passes loosely through the recesses 35 O between the lugs P and through opening V in the stirrup, so that the foot may be moved or slid through the guides and through the stirrup when adjustment in 40 different positions is desired, but the clamping effect is obtained with any tipping of the ladder out of the vertical when the foot is braced against the abutment, and this binding or clamping effect takes place no matter whether the foot is on level ground 45 or on broken ground. The ladder is automatically clamped to the foot in any position and the clamp is released whenever desired.

I claim and desire to obtain by Letters 50 Patent the following:

1. An adjustable foot for ladders adapted

to be attached to the lower ends of the sides of a ladder, and comprising a brace rod adapted to be secured transversely between the sides of the ladder, guide plates adapted 60 to be secured to the ladder sides, a stirrup clamp pivotally hung from the brace rod, and a bow-shaped foot passing through the stirrup clamp and guided but capable of rocking in the guide plates.

2. An adjustable foot for ladders adapted to be attached to the lower ends of the sides of a ladder, and comprising a brace rod adapted to be secured transversely between the sides of the ladder, guide plates adapted 70 to be secured to the ladder sides, a stirrup clamp pivotally hung from the brace rod, said stirrup clamp having an angular opening, and a bow-shaped foot of angular cross section passing loosely through the angular 75 opening in the stirrup clamp, whereby angular displacement of the plane of the ladder relatively to the plane of the foot causes the foot to bind in the stirrup and prevents the ladder from slipping sidewise on the 80 foot.

3. An adjustable foot for ladders adapted to be attached to the lower ends of the sides of a ladder, and comprising a brace rod adapted to extend transversely of the ladder 85 sides, a stirrup clamp pivotally hung on the brace rod, and a bow-shaped foot of angular cross section passing loosely through the stirrup clamp, whereby the foot is caused to bind in the stirrup when the ladder is tipped angularly relatively to the plane of the foot.

4. An adjustable foot for ladders adapted to be attached to the lower ends of the sides of a ladder, and comprising a brace rod 95 adapted to extend transversely of the ladder sides, a bow-shaped foot loosely connected to the brace rod, said loose connection being constructed to automatically cause a binding action to take place between the 100 foot and said connection when the ladder is tipped out of the plane of the foot, thereby preventing the ladder from slipping along the longitudinal length of the foot.

In testimony whereof I have signed this 105 specification in the presence of two subscribing witnesses.

WILLIAM D. OSTERHOUDT.
